UNITED STATES PATENT OFFICE.

JOHAN FREDERICH ANDERSON, OF POPLAR GROVE, ILLINOIS.

COMBINATION TABLE AND CHAIR.

1,237,600.

Specification of Letters Patent. Patented Aug. 21, 1917.

Application filed January 8, 1916. Serial No. 71,125.

To all whom it may concern:

Be it known that I, JOHAN FREDERICH ANDERSON, a citizen of Sweden, residing at Poplar Grove, in the county of Boone and State of Illinois, have invented certain new and useful Improvements in Combination Tables and Chairs, of which the following is a specification.

My present invention relates to collapsible tables and chairs, and more particularly to a device comprising both a table and chair; having for its primary object the provision of a structure adapted to be installed in a baby-carriage, thus providing a table and tray for holding the usual display of toys, etc.

Another object of my invention is to provide new and novel means for locking the collapsible edges of the table in a vertical position.

A further object of my invention is to provide a means, such as a back of a chair, adapted to be part of the table, and capable of being converted therefrom into a chair.

Having these and other objects of general utility and design in view, I have illustrated a preferred and operative form of my invention in the accompanying drawings, in which:

Figure 1 is a perspective view of my device in the form of a table;

Fig. 2 is an elevation thereof, shown assembled in a baby carriage, the side rails of the table being shown in their vertical position;

Fig. 3 is a perspective view of my device shown opened into a chair;

Fig. 4 is an enlarged fragmental detail plan of one corner of the table as shown in Fig. 2 the rail being locked in its vertical position, and

Fig. 5 is a transverse section on line 5—5 of Fig. 4.

Similar reference characters refer respectively to the similar parts throughout the several views.

The structure as illustrated in the drawings comprises a substantially rectangular plate 10, so constructed as to serve either as a chair seat or table top, being pivoted at its four corners to the upper ends of two sets of collapsible legs 11, the same being pivoted intermediate their ends, having a transverse bar 12 and thumb screw 13 connecting the same at this point. Hinged at 14 to the upper peripheral edge of the plate 10, are rails 15, adapted to be swung perpendicular

to the plate as shown in Figs. 2, 4 and 5, being held in this position by means of a pivoted segmental shaped button 16, the periphery of which contacts the inner perpendicular wall of the rails at their intersecting corners (Figs. 4 and 5) when open, and when folded down adjacent the top of the table or plate 10, the button is rotated to a position in which it fits in a recess 17 in the plate 10, thus making the top of the table an even, substantially level, surface. Butt-joint links or arms 18 are pivoted at 19 to the legs 11, which links fold back in recesses 20 on their sides, but which may be extended so as to serve as feet to contact the rail 21 of the baby-carriage 22 as shown in Fig. 2.

A chair back 23, is pivoted at 24 along the under rear edge of the plate 10, the forward edge of which is held adjacent the under side of the plate by means of a suitable hook or lock 25. Auxiliary legs 26, having a slot extending throughout their length, are mounted (one on each side) adjacent one of each of the sets of the legs 11, engaging the rod 12 and rear pivot of the leg 11. The lower ends of the legs 26 are bent at an appreciable angle thereto, their upper ends being connected by a transverse rod 27.

It will be obvious that when it becomes desirable to change the table as shown in Figs. 1 and 2 to the chair as shown in Fig. 3, the operator first unhooks the member 23 from the plate 10 at 25, allowing the same to pivot at 24, swing down and then up (Fig. 3). The set screw 13 is loosened and the legs 26 drawn upwardly and inwardly (due to the curved portion of the leg). A rod 27 is removably secured in the upper end of the slots in legs 26 and is retained in the position illustrated in Fig. 1 by means of pins 23' carried by the back 23 or in the absence of such pins merely by frictional engagement with the said back for which it serves as a stop. The rod 27 may be removed by manually drawing it out of engagement with the said legs 26.

What is claimed is:

1. A combination table and chair comprising a horizontally disposed substantially rectangular plate, a chair back hinged thereto along the under rear edge thereof, a lock securing the forward edge of said back adjacent the under side of said plate, suitable legs pivoted at the four corners of said

105

110

plate, a transverse rod connecting the same intermediate their ends, slotted bars engaging said rod and the rear pivots of said legs respectively, a rod removably connecting the upper ends of said bars, said last mentioned slotted bars having their bottom ends curved at an angle thereto.

2. A combination table and chair comprising a substantially rectangular plate, a chair 10 back hinged thereto, means securing said back adjacent said plate, suitable legs pivoted to said plate, a bar connecting said legs,

slotted bars engaging said bar and the rear pivots of said legs respectively and a rod removably connecting the upper ends of said 15 slotted bars.

In testimony that I claim the foregoing as my own I have hereto affixed my signature in the presence of two subscribing witnesses.

JOHAN FREDERICH ANDERSON.
